UNITED STATES PATENT OFFICE.

JOHN HELM AND HENRY C. HELM, OF ST. LOUIS, MISSOURI.

DESIGN FOR A FACEPLATE FOR MAIL RECEPTEACLES.

Application filed May 4, 1925. Serial No. 13,312. Term of patent 14 years.

To all whom it may concern:

Be it known that we, JOHN HELM and HENRY C. HELM, citizens of the United States, residing in the city of St. Louis, State of Missouri, have invented a new, original, and ornamental Design for a Faceplate for Mail Receptacles, of which the following is a specification, reference being had to the accompanying drawing, forming part thereof, and the figure of which is a face view of a faceplate for mail receptacles showing our new design.

We claim:

The ornamental design for a faceplate for mail receptacles, as shown.

JOHN HELM.
HENRY C. HELM.
